ICE AND SNOW SCRAPER

Paul H. Grinnell, 9437 Dorothy Ave., Garfield Heights,
Ohio 44125, and Carl D. Vajdich, 18801 Waterbury
Ave., Maple Heights, Ohio 44137

Filed Sept. 9, 1974, Ser. No. 504,298

Term of patent 14 years

Int. Cl. D7—05

U.S. Cl. D7—184

FIG. 1 is a top plan view of an ice and snow scraper, showing our new design;

FIG. 2 is a side elevational view; and

FIG. 3 is a bottom plan view thereof.

We claim:

The ornamental design for an ice and snow scraper, substantially as shown.
